UNITED STATES PATENT OFFICE.

JOHN VELCIO, OF YOUNGSTOWN, OHIO, ASSIGNOR OF ONE-THIRD TO CHARLES A. HARPMAN, OF YOUNGSTOWN, OHIO.

COMBINATION PNEUMATIC CASING.

1,377,375.

Specification of Letters Patent. Patented May 10, 1921.

Application filed February 24, 1921. Serial No. 447,588.

To all whom it may concern:

Be it known that I, JOHN VELCIO, citizen of the United States of America, residing at 110 West Woodland avenue, Youngstown, 5 in the county of Mahoning and State of Ohio, have invented certain new and useful Improvements in Combination Pneumatic Casings, of which the following is a specification.

10 This invention relates to tires, and more particularly to casings for pneumatic tires.

The principal object of this invention is to provide a tire casing having a removable tread portion in order to place the same 15 with a new tread when the old tread has become worn out.

Another object is to provide a base portion for said tread for the purpose of making the casing practically free from punctures and at the same time providing a securing means for holding the removable tread in position.

Another object is to provide an upper edge of the side walls of the casing having 20 incased therein a metallic cord or wire.

A still further object is to provide a filler part at each side of the casing.

The drawing illustrates the preferred embodiment of the invention. However, it is 30 to be understood that in adapting the same to meeting different conditions, various changes in the form, and minor details of construction may be resorted to without departing from the nature of the invention as 35 claimed and set forth in the drawing:

The figure is a perspective view of my improved casing showing a cross section of the same.

40 Corresponding and like parts are referred to in the following description; and indicated in the drawing by like reference characters.

It will be seen that I have provided an ordinary base 1 for placement upon a rim.

45 The casing 2 is provided with a web portion 3 having bifurcated ends 4 which are secured to the side walls 5. Within the bifurcated ends 4 and the side walls 5, I have provided a filler 6 which strengthens

the upper portion of the side wall 5 and 50 also thickens the wall at this place, thereby practically eliminating the puncturing of an inner tube within the casing 2 from side penetration.

I have provided upper edges 7 on the side 55 walls 5. These upper edges 7 have incased therein metallic cords or wires 8 for the purpose of holding the edges 7 within the channels 9, which are formed near each of the outer edges of the tread 10. The tread 10 60 is provided with overlapping wings 11 which fit down over the side walls 5 at points 12. In order to provide a removable tread 10, I have provided a base portion 13 which rests upon the web portion 3 and fits 65 underneath and against the inner curved portion 14 of the side walls 5. In order to give a certain degree of elasticity and resiliency in the tread 10, I have provided a core 15 centrally located in the base portion 70 of the tread, this core 15 to be formed of a soft rubber material. Surrounding this core 15, I have provided reinforcing webs 16 which will also act as a resisting means 75 against puncture.

It will be seen that the space usually occupied by an inflated tube has been reduced and it is my purpose to use an inner tube of a smaller circumference than would otherwise be used in a casing having similar dimensions to my improved casing.

What I claim is:

In a device of the class described, a casing provided with two outer walls, a support web, bifurcated ends on said web securely attached to said side walls, a filler secured within these bifurcated ends and outer wall, an upper edge of side walls, a channel in sides of tread, a wing portion overlapping said upper edge, a metallic bond incased in said upper edge of casing, substantially as described for the purpose set forth.

In testimony whereof I affix my signature.
JOHN VELCIO.

Witnesses:

A. E. BURKY,
C. A. HARPMAN.
